SHAVER HEAD MOUNTING

Louis C. Carissimi, Fairfield, Conn., assignor to
Remington Rand Inc., Buffalo, N. Y., a corpora-
tion of Delaware

Application June 27, 1942, Serial No. 448,711

10 Claims. (CL. 30—43)

This invention relates to dry shavers and particularly to a mounting or clamping device for detachably securing the shaver heads to the casing.

The invention is provided for securing either a single shaver head or a plurality of shaver heads in a convenient manner and in detachable relation on a shaver casing, for the purpose of eliminating the disadvantage of exposed screw heads on that part of a shaver case that may come in contact with the face or neck in shaving; providing a fastening means whose strength can be pre-determined and caused to break if excessive torque is applied thereto thereby preventing breakage and cracking of the case; providing a device that retracts the shaver head engaging parts when pressure is released, to avoid complete removal of the attaching device but allowing free detachment and replacement of shaver heads; providing a clamping device for securing shaver heads on casings with or without apertures in the shaver heads; and providing for improving the appearance of shavers through the location of the head mounting device where it does not project out through the casing at a location where it is prominent and interferes with the design of the exterior of the shaver casing.

In the drawing:

Fig. 1 is a longitudinal fragmentary cross section through a shaver having two heads mounted on one end, the proportion in the drawing being greater than actual size, and the head clamping means being illustrated in the position in which the heads are secured to the casing in operative position.

Fig. 2 is a cross section taken on line 2—2 of Fig. 1 with portions broken away for convenience in illustration.

Fig. 3 is a cross section taken on line 3—3 of Fig. 1, portions being broken away.

1 indicates the shaver casing which will include a removable cover 2 mounted on the casing in any suitable manner so as to provide a cover for the compartment housing the motor (not shown). The oscillator 3 of conventional form is illustrated diagrammatically in Fig. 1 and is arranged in one end of the compartment with the motor for operation thereby in a well-known manner. Oscillator 3 is accessible for removal, inspection and replacement upon removal of cover 2 along with the motor.

One end of shaver casing 1 is formed to provide a channel structure. In the illustration in the drawing, the casing is illustrated as having two channels 4 arranged in spaced relation and

extending transversely across one end of casing 1 in parallel relation to one another and opening through the end of casing 1. A web portion 5 of the casing forms a dividing or partition wall between channels 4. The shaver illustrated is constructed to receive two shaver heads 6 of conventional construction having base portions 7 and shaving sections 8 forming the stationary cutter structure that may be of any form well-known in the art. These heads 6 have inner reciprocable cutters 9 of conventional form that are engaged by the ends of oscillator 3 as illustrated in Figs. 1 and 2 for reciprocating the inner movable cutters for shaving operation with the shaving sections 8.

These shaver heads 6 have their base portions engaged in channels 4 as shown in the drawing so that the bottom of each base portion seats in the bottom or inner portion of one of the channels in the casing, one head being mounted in each channel 4. If desired, partition 5 may under some conditions be omitted or provided as a separate part without interfering with the operation of the present invention which is directed particularly to the means for securing the heads in operative position on casing 1 as shown in the drawing.

For the purpose of the present invention each shaver head 6 will be provided with a suitable structure to provide a shoulder at 10. This shoulder 10 may be formed in any suitable manner in the shaver head such as by forming a slot or opening 11 in the side wall of the stationary cutter structure.

35 A clamping member is formed by a strip of resilient or flexible sheet metal or other suitable material, formed into U-shape with laterally extending arms or head engaging projections 13 provided on the free ends of the U-shaped structure. Arms 13 in extending laterally from ends of the arms of the U-shaped structure of the clamping member operate to provide shoulder engaging portions for engaging shoulders 10 of shaver heads 6, in the manner illustrated in the drawing. The U-shaped portion of clamping member 12 as shown in Figs. 1 and 2, for example, is located between the shaver heads in a recess 14 formed in partition 5, said recess being of rectangular cross section in plan view as shown in Fig. 2. Clamping member or retaining means 12 slidably engages between the adjacent side walls of shaver heads 6 in the central portion thereof when arms 13 are engaged in slots 11. The central section of clamping member

12 is formed with an opening 15 through which extends securing member 16.

Securing member 16 is in the form of a screw having a head 17 with a cam portion 18 of frustoconical shape formed at the juncture of head 17 with a reduced section 19 of the screw shank. The opposite end of the screw shank extending beyond reduced section 19 is enlarged in diameter and threaded as indicated at 20 for threaded engagement in anchor member 21. Anchor member 21 is in the form of a rectangular block structure slidably engaged in a socket formed in casing 1 as illustrated in Figs. 1 and 3, and as having an internally threaded bore receiving threaded end 20 of securing member 16.

The head mounting members are shown in operative position for clamping the two heads illustrated in operative position on casing 1. When it is desired to remove either or both of the shaver heads, securing member or screw 16 is moved to unthread shank 20 from block 21. This will move head 17 and cam portion 18 upwardly as illustrated in Fig. 1 to disengage from the ends of U-shaped clamping member 12. The resiliency and flexibility of clamping member 12 and its U-shaped construction will normally cause the arms of the U-shaped member with laterally projecting arms 13 on the ends thereof to move inwardly toward each other and the screw shank so that when head 17 and cam portion 18 have moved upwardly to a sufficient extent, arms 13 will move toward each other into a position where they will be disengaged from shoulders 10 and openings 11 in the shaver heads. This position of securing member 16 will not necessitate its disengagement from anchor member 21.

With the securing screw 16 in the disengaging or release position either head may be readily removed and replaced in its position in channel 4 of casing 1. In this way the heads can be interchanged, or replaced, or removed for cleaning and repairs. The clamping mechanism does not have to be disengaged from casing 1 while clamping member 12 is held in position by recess 14 in partition 5 so that it does not rotate with securing member 16.

Upon replacement of the heads into the position shown in Fig. 1 in channels 4 of casing 1, operation of screw securing member 16 to thread the same inwardly into anchor block 21 will move cam face 18 into engagement with laterally extending arms 13 and the ends of the arms of the U-shaped structure of clamping member 12. Continued movement of securing member 16 will flex the arms of clamping member 12 laterally outward relative to the longitudinal dimension of the casing of member 16 to engage lateral projections 13 in openings 11 and with shoulders 10 on the shaver heads. Continued operation of screw 16 in this direction will move clamping member 12 toward anchor block 21 and move heads 6 toward the bottom of the channels until the bottom portions of base portions 7 engage the bottom portions of the channel to firmly seat in the channels where the shaver heads will be rigidly held in seated position on casing 1 for the normal operation of the shaver.

The reduced section 19 of the shank of securing member 16 is pre-determined to provide a weak portion in the shank of member 16 adapted to break whenever the tension or torque on securing screw 16 becomes too great. The shank 19 of securing screw 16 will break before the pressure rises to such an extent that it will cause casing 1 to crack or break at any point. This

feature is provided due to the fact that the conventional shaver casings now used are made of molded plastic material having limited strength and, therefore, subject to cracking or breaking when excessive strains are applied thereto.

It will be noted from the arrangement of the head clamping and securing means of the present invention that it is located in a substantially concealed position between the bases of the heads where two heads are used on a shaver casing. The clamping means operates in the same direction as that in which the heads are applied and removed in the channels in casing 1, which is longitudinally relative to the general shape of the casing. The clamping means does not have to be removed from engagement with the casing to provide for disengagement of the heads from their channels. Arms 13 extend laterally in inclined relation and have a camming action as they are moved laterally apart for camming the heads toward the bottom of the channels.

The present invention eliminates the use of securing or clamping screws on the outside portions of the casing in a conspicuous position as heretofore well-known in the art, eliminates the tendency of these portions of the casing to crack and the necessity in most cases of having to provide the outside portions of the casing structure adjacent the shaver heads with an increased cross sectional dimension to provide sufficient strength to mount the clamping screws and provide for the distribution of stresses.

Therefore, the present invention provides for substantially concealing the head clamping mechanism; provides a structure for fastening the shaver head securely on the casing that may be used for either single or multiple heads; eliminates prominently exposed screw heads at the outside of the casing adjacent the shaver heads that may come into contact with the face or neck during shaving; provides a fastening means whose strength is pre-determined whereby it will break if excessive torque is applied thereto for preventing breakage of the case; provides a clamping means that can be used with the heads with or without apertures in the heads or any complementary construction between the clamping means and the heads that will provide for interengagement thereof; and provides a device that will retract when the securing pressure is released so as to eliminate complete removal of the clamping device and at the same time allowing free replacement of the heads. The invention further provides a structure wherein the clamping means is concealed in a way that it does not disfigure the exterior appearance of the casing and thereby provides for the designing of the casing adjacent the heads to enhance its appearance in a much more desirable manner than has heretofore been feasible.

The invention claimed is:

1. A shaver head mounting wherein a casing is formed to receive and support a pair of shaver heads in spaced parallel relation on one end, comprising a clamping member between said heads, having oppositely projecting head engaging projections for simultaneously engaging both heads, and retaining means mounted on said casing, engaging said clamping member and operable to firmly move and retain said clamping member in engaged relation with said shaver heads for retaining said heads operably attached to said casing.
2. In a shaver having a casing formed to de-

tachably receive a pair of shaver heads in spaced parallel relation projecting in the same direction outwardly from said casing, said heads having base portions engaged with the casing and shoulders formed on adjacent side portions, means for mounting said heads in attached relation on said casing, comprising a clamping member having arms engaging said shoulders on said heads and an intermediate portion guided by complementary portions of said casing, and casing carried securing means movable toward and from said casing operable in movement toward said casing to engage said clamping member and move it toward said casing for moving said heads through the engagement of said arms with said shoulders to firmly seat and retain said heads in position on said casing.

3. In a shaver having a casing formed at one end to receive a plurality of heads in spaced relation having base portions detachably engaged with seats on the casing and shaving portions projecting outwardly from the casing in substantially the same direction, and said heads having shoulders formed on adjacent sides, a head mounting means comprising a clamping member having a pair of arms, one for engaging the shoulder on each adjacent head, and a securing member carried by said casing for movement toward and from the casing in the same direction as the heads are moved to engage and disengage said seats, for engaging said clamping member and moving it with said heads toward said seats and casing in the movement thereof toward said casing for detachably retaining said heads on said seats and casing.

4. In a shaver having a casing formed with a channel means to slidably receive the base portions of outwardly projecting separate shaver heads carried thereby, means for detachably mounting said heads on said casing comprising a clamping member engaging between adjacent heads and having a pair of laterally movable arms each engaging one of said adjacent heads, and casing carried means engaging said clamping member operable to laterally move and retain said arms engaged with said heads and to move said member and heads toward said casing in said channel means to firmly engage said casing in attached operative relation of said heads thereon.

5. In a shaver having a casing formed with a channel to slidably and detachably receive the base portion of an outwardly projecting shaver head, means for mounting said shaver head in operative relation on said casing comprising a clamping member having an arm movable laterally to engage a complementary portion of said shaver head, and casing carried means engaging said clamping member operable to move said arm laterally to engage said head and also move said member toward said casing with said head to engage and firmly retain said head in position on said casing for shaving operation.

6. In a shaver having a casing formed with a channel to slidably and detachably receive the base portion of an outwardly projecting shaver head, means detachably mounting said shaver head in operative relation on said casing comprising a clamping member slidably engaged with a side of said head and a portion of said casing for relative movement, a head engaging arm on said clamping member movable laterally to the direction of movement of said member for engaging a portion of said shaver head when moved

laterally in one direction, and an operating screw threaded in said casing and having an outwardly extending shank portion carrying a screw head at the outer end for operating said arm to move laterally to engage said shaver head and move said clamping member with said arm and shaver head into clamped position on said casing when said operating screw is operated to move the screw head toward said casing.

10 7. In a shaver having a casing formed with channel means to slidably receive the base portions of a plurality of shaver heads with shaving sections projecting outwardly in the same direction in spaced relation, a head mounting comprising a flexible strip forming a clamping member engaged between said heads and having an intermediate section and a pair of arm sections flexibly extending from said intermediate section, said arm sections having the free ends engaging adjacent sides of adjacent shaver heads, and a securing member carried by said casing movable toward and from said casing and operable in movement toward said casing to engage and project said arm sections laterally to engage and move said heads into clamping position on said casing.

8. In a shaver having a casing formed with channel means to slidably receive the base portions of a plurality of shaver heads in spaced substantially parallel relation with shaving sections projecting outwardly in the same direction, a head mounting comprising a clamping member formed of a resilient strip having a U-shape in cross section, the leg portions of said U-shaped member forming arms having laterally extending end portions for interengagement with portions of adjacent sides of a pair of shaver heads with the remaining portions of said clamping member extending therebetween, said casing having a recess therein for slidably receiving said U-shaped clamping member therein throughout the portion extending between said shaver heads, an anchor block mounted in a socket in said casing in aligned relation with the recess receiving said clamping member, and a retaining screw threaded in said anchor block having a cam portion formed thereon for engaging the free ends of the arms of said clamping member for projecting them laterally into engagement with said shaver heads, said retaining screw upon being operated to move inwardly toward said casing and blocks operating said clamping member for moving said heads so that the base portions will be firmly seated in said channel means in said casing for being firmly held in attached relation on said casing for shaving operation thereon.

9. In a shaver head having a casing formed with channel means to slidably receive the base portions of a plurality of shaver heads with shaving sections projecting outwardly in the same direction in spaced relation, a head mounting comprising a clamping member formed of a resilient strip member having a U-shape engaged in a recess in said casing between adjacent shaver heads, the ends of the legs of said U-shaped strip having laterally extending head engaging arms thereon normally moved inwardly through the resilience of the material of said strip into disengaged relation relative to said heads, an anchor block mounted in the casing in aligned relation with the recess receiving said clamping member, a screw threaded in said anchor member having a shank extending outwardly relative to said casing and formed with a camming head on the free end

and a portion of reduced cross section intermediate said head and the portion threaded in said anchor member, said head being adapted for engagement with the laterally extending arms of said clamping member for camming said arms outwardly in opposite directions upon screw threaded movement of said clamping screw into said anchor member for moving said arms outwardly into engagement with adjacent shaver heads and for further moving said heads to firmly seat and hold the base portions of said shaver heads in rigidly engaged relation in said channel means in operative relation on said casing.

5
10

10. In a shaver having a casing formed with a channel to slidably and detachably receive the base portion of an outwardly projecting shaver head, means for mounting said shaver head in operative relation on said casing comprising a clamping member for engaging said head, a securing member having a cam portion for engaging and moving said clamping member into seated operative engagement on said casing and means responsive to excessive torque in the operation of said securing means operable to protect said casing against breakage.

LOUIS C. CARISSIMI.
